CLAMP FOR CUTTING MACHINES

Robert F. Heyman, South Westville, N. J.

Application July 6, 1932, Serial No. 621,113

12 Claims. (Cl. 164—59)

This invention relates to new and useful attachments for paper cutting machines and particularly to paper cutting machines of the guillotine type.

5 The principal object of the invention is to provide a device for use in conjunction with machines of the above character which will effectively clamp a stack of sheets of paper in the machine and prevent slipping or twisting of the respective sheets during the cutting operation.

Another object of the invention is to provide a device of the present character which effectively clamps and locks the stack of sheets of paper in a firm grip in the machine during the 15 entire cutting operation.

Another object of the invention is to provide a device as described wherein the paper is clamped and locked in position automatically when the paper is placed in the machine, and is 20 automatically unclamped when the paper is removed after being cut.

A more specific object of the invention is to provide a novel clamping device as set forth which may be attached to the customary back 25 gage of a cutting machine and when once in position is automatic in operation and relieves the operator of the machine from attending or operating the clamp.

Other objects and details of construction of the 30 invention are set forth hereinafter and shown in the accompanying drawing, in which:

Figure 1 is a fragmentary view in section of a cutting machine showing the device constituting the present invention associated therewith;

35 Fig. 2 is a view in plan of the device;

Fig. 3 is a view in side elevation of the device disclosed in Fig. 2 having a portion of the back gage cut away to show the mounting of the clamping device.

40 Fig. 4 is a view similar to Fig. 3 showing the device in locked position to firmly clamp the stack of paper in the machine; and

Fig. 5 is a view in perspective of portions of the clamping device which are available to alter 45 the size thereof for various sizes of stacks of sheets to be cut.

Heretofore, in paper cutting machines of the present character, considerable difficulty has been present in a tendency for the respective 50 sheets of a stack to twist a small degree with respect to each other, causing the uneven cutting thereof. Certain clamping devices have been devised and adapted to travel with the cutting knife and clamp the paper with increasing force as the cutter descends through the stack.

These clamps have been only partially successful since the stacked sheets were not clamped on the machine table immediately upon the placing of the paper in the machine.

By the present invention a clamping device is 60 provided for locking stacked sheets of paper in a cutting machine immediately the stack is placed in the machine in position for cutting. The paper is firmly locked in position and will so remain until such time as the paper is removed therefrom. The clamp is automatic in 65 operation, requires no attention when once set, and clamps the stacked paper irrespective and independently of the operation of the cutter and other movements of the machine. 70

Referring now more particularly to the drawing, the invention is shown in conjunction with a paper cutting machine comprising side frame members 1 separated by channel or other members 2 and having the customary table 3 on which the stacked sheets of paper A rest. A back gage 4 is adjustably mounted on the rear portion of the table 3 and is provided with a plurality of forwardly extending parallel spaced fins or flanges 5 against the forward ends 5a 80 of which the stacked sheets of paper A abut. The customary knife stock 6 carrying a knife blade 7 moves vertically between guide members 8 and 9 respectively. 85

The novel clamping device forming the subject of the present invention comprises a bracket 85 consisting of sides 10 and 11 respectively which are spaced with respect to each other by an end piece 12 residing intermediate said side members and adjacent the rear thereof. The bracket is 90 arranged to be positioned in the space intermediate the parallel flanges 5 of the back gage 4, as shown in Figs. 3 and 4 of the drawing and it should be noted that the width of the bracket just described, may be substantially equal to 95 the width of the space intermediate the flanges 5 so that the bracket will fill the space and be more firmly supported by the back gage, the said bracket being firmly secured in the space intermediate the flanges 5 by any means and such a 100 bolt 14.

It should be further noted that the forward ends 13 of the sides 10 and 11 of the bracket, reside in a plane substantially flush with the forward end surface 5a of the flanges 5 so that 105 the operation of the clamping device will not be interfered with.

An arm 15 is pivotally mounted as at 16, intermediate the sides 10 and 11 of the bracket and it should be noted that the pivot point 16 110

thereof is offset forwardly from the vertical center line of the said arm 15 and is so positioned with respect to the sides of the bracket that the forward end face 15a thereof is substantially flush with the forward end faces 13 of the sides of the bracket and the forward end faces 5a of the flanges 5 when in the position to clamp a stack of sheets.

The arm 15 pivots about the point 16 against the action of a spring 17, one end of which is connected to a pin 18 residing in the recess 19 formed in the rear end face of said arm, the other end of the said spring being adjustably connected to the member 12 by means of a screw 20 which cooperates with a threaded element 21 threaded into the rear end of the spring. The arrangement just described permits the tension of the spring to be adjusted so that sufficient force may be exerted on the pivotal arm to maintain said arm in its normal position. Grooves 22 and 23 are formed adjacent the extremity of the forwardly projecting portion 13b of the arm 13 in such a manner as to provide a substantially vertical runner 24 arranged to reside in a slot 25 in the clamp member 26.

The vertical position of the member 26 with respect to the projection 13b of the arm may be predeterminedly fixed by suitable adjusting means such as a wing nut 27 and bolt 28 which extends through the slot 25 in the clamp piece 26.

An extension 29 is provided and is arranged for positioning intermediate the lower extremity of the member 26 and a contact piece 30 so that the clamp may be readily adjusted for effective use with stacks of sheets of various heights. The lower end of the member 26 is provided with an inwardly extending bore 31 arranged to receive a projection 32 on the extension 29 and retained therein by a lock bolt 32. The upper surface of the contact piece 30 is provided with a similar projection 32a arranged for insertion in the inwardly extending bore 31 in the clamp piece 26 or a similar bore 33 in the lower extremity of the extension 29 as may be desired, depending upon the height of the stack of sheets to be cut.

The normal position of the clamp, when there is no stack of material in position for the cutting operation, is disclosed in Fig. 3 of the drawing, the said clamp being normally maintained in that position, by the action of the spring 17 described above.

When a stack of sheets of material is to be cut, the back gage 4 is adjusted upon the table 3 in order that the sheets cut by the knife 9 will be of the desired predetermined dimension when one side of the stack of sheets is in abutting relation with the ends 5a of the parallel spaced flanges 5 of the said gage 4. When a stack of sheets A abuts the ends of said flanges 5 in the manner set forth, that part of the arm 15 normally projecting outwardly beyond the end faces 5a of the flanges below the pivot point 16, is moved inwardly intermediate the sides 10 and 11 of the bracket and the forward end face 13a of the arm 15 assumes a position flush with the ends of the bracket and the flanges 5a causing the contact piece 30 to correspondingly pivot and engage the top sheet of the stack A with sufficient pressure to firmly maintain the sheets in proper relation during the cutting operation.

It should be noted particularly that the longitudinal axis of the runner or guide 24 is disposed at an angle obliquely with respect to the vertical center-line of the arm 15 and positions the clamp

element similarly at an angle with respect to said arm.

As shown in Fig. 4, when the member 30 contacts with the uppermost sheet of paper, the clamp extends inwardly from its upper end at an angle oblique to the now true vertical center-line of the arm 15. This arrangement of the clamp effectively locks the stacked sheets A firmly in position for the cutting operation and prevents the relative twisting of the several sheets with respect to each other during the vertical downward passage of the knife blade 7. The sheets will be firmly held by the clamp in the manner set forth irrespective of any other operation of the machine until the stack of cut sheets is moved away from the flanges 5, to permit the spring 17 to pivot the arm 15 about the point 16 and releasing the member 30 from contact with the sheets.

While I have set forth the embodiment of my invention for the purpose of description, it will be apparent that certain modifications in the detailed construction thereof and certain changes in form necessarily incident to its application to cutting machines of various forms, may be incorporated within the scope of the appended claims.

What is claimed is:

1. In a cutting machine having a bed for supporting material to be cut, a back gage, and means pivotally mounted with respect to said gage for automatically clamping and locking said material firmly on the bed when the material abuts the gage in position for cutting, said means automatically releasing the material immediately said material is removed from contact with said gage.

2. In a cutting machine having a bed for supporting material to be cut, a back gage, means pivotally mounted with respect to said gage for clamping the material firmly on the bed as long as the material abuts the back gage, and means operable to release the clamp and free the material immediately said material is removed from contact with the back gage.

3. A clamping device comprising a bracket, an arm pivotally mounted with respect to said bracket, the pivot point for said arm being offset forwardly of the longitudinal center line of said arm and suitably positioned so that, when the arm is in a vertical position, the front end face thereof will be flush with the front end face of the bracket, a contact arm carried by said pivot arm and disposed at an angle oblique to the longitudinal center line of the latter, and means connected intermediate the pivot arm and the bracket tending to pivot the former and raise the contact arm.

4. A clamping device comprising a bracket, an arm pivotally mounted with respect to said bracket, the pivot point for said arm being offset forwardly of the longitudinal center line of said arm and suitably positioned so that, when the arm is in a vertical position, the front end face thereof will be flush with the front end face of the bracket, an adjustable contact arm carried by said pivot arm and disposed at an angle oblique to the longitudinal center line of the latter, and a spring connected intermediate the pivot arm and the bracket tending to pivot the former and raise the contact arm.

5. A cutting machine having a bed for supporting material to be cut, a cutting knife movable vertically with respect to the table, a back gage adjustably mounted on the bed, said back

- gage having forwardly extending spaced parallel flanges thereon, means for clamping the material to the bed mounted in the space intermediate said flanges, said means comprising a bracket, the outer end faces of which are flush with the end faces of the flanges, an arm pivotally mounted in said bracket, the pivot point thereof being offset forwardly of the longitudinal center line of the arm and positioned in the bracket so that when said arm is substantially vertical the front end face is flush with the ends of the bracket 80
- 5 10 15 20 25 30 35 40 45 50 55 60 65 70 75 80 85 90 95 100 105 110 115 120 125 130 135
- when said arm is substantially vertical the front end face is flush with the ends of the bracket and the flanges of the gage, a contact arm adjustably mounted on the pivot arm and disposed at an angle oblique with respect to the vertical center line of said pivot arm, and a spring connected intermediate the pivot arm and the bracket acting to pivot the arm in a clockwise direction and maintain the contact arm out of engagement with the material to be cut when said material does not abut the end faces of the bracket and flanges.
6. A cutting machine having a bed for supporting material to be cut, a cutting knife movable vertically with respect to the table, a back gage adjustably mounted on the bed, said back gage having forwardly extending spaced parallel flanges thereon, means mounted in the space intermediate said flanges for securing the material to the bed, said means comprising a bracket, an arm pivotally mounted in said bracket, the pivot point thereof being offset forwardly of the longitudinal center line of the arm, and a contact arm adjustably mounted on the pivot arm and disposed at an angle oblique with respect to the vertical center line of said pivot arm.
7. A cutting machine having a bed for supporting material to be cut, a cutting knife movable vertically with respect to the table, a back gage adjustably mounted on the bed, said back gage having forwardly extending spaced parallel flanges thereon, means mounted in the space intermediate said flanges for clamping the material to the bed, said means comprising a bracket, an arm pivotally mounted in said bracket, the pivot point thereof being offset forwardly of the longitudinal center line of the arm, a contact arm adjustably mounted on the pivot arm and disposed at an angle oblique with respect to the vertical center line of said pivot arm, and a spring connected intermediate the pivot arm and the bracket acting to pivot the arm and move the contact arm out of engagement with the material when removed from contact against the back gage.
8. A cutting machine having a bed for supporting material to be cut, a back gage mounted thereon, means mounted in the back gage for clamping the material to the bed, said means comprising a bracket, an arm pivotally mounted
- in said bracket, the pivot point thereof being offset forwardly of the longitudinal center line of the arm and positioned in the bracket so that when said arm is substantially vertical the front end face is flush with the ends of the bracket and the gage, a contact arm adjustably mounted on the pivot arm and disposed at an angle oblique with respect to the vertical center line of said pivot arm, and a spring connected intermediate the pivot arm and the bracket acting to pivot the arm in a clockwise direction and maintain the contact arm out of engagement with the material when removed from contact against the back gage.
9. A cutting machine having a bed for supporting material to be cut, a gage mounted thereon, means mounted on said gage for clamping the material to the bed, said means comprising a bracket, an arm pivotally mounted in said bracket, a contact arm adjustably mounted on the pivot arm and disposed at an angle oblique with respect to the vertical center-line of said pivot arm, and means connected between the pivot arm and the bracket, tending to pivot said arm and maintain the same out of engagement with the material when the latter is removed from contact against the gage.
10. A cutting machine having a bed for supporting material to be cut, a back gage adjustably mounted on the bed, said back gage having forwardly extending spaced parallel flanges thereon, means mounted in the space intermediate said flanges for clamping the material to the bed, said means comprising a bracket, an arm pivotally mounted in said bracket, a contact arm adjustably mounted on the pivot arm, and a spring connected intermediate the pivot arm and the bracket acting to pivot the arm and move the contact arm out of engagement with the material when removed from contact against the back gage.
11. In a machine for cutting through stacks of sheets of paper, means associated with said machine and operable independently thereof to automatically engage said stack when the latter is in cutting position and prevent relative movement of said sheets with respect to one another, said means also being automatically operative to release said stack when the latter is removed from cutting position.
12. In a machine for cutting through stacks of sheets of paper, the combination with a gauge, of means operatively associated therewith to automatically engage said stack when abutting said gauge and prevent relative movement of said sheets with respect to one another, said means also being automatically operative to release said stack when the latter is removed from contact with said gauge.

ROBERT F. HEYMAN. 135
